US00D631353S

(12) **United States Design Patent**
Gelardi et al.

(10) **Patent No.:** **US D631,353 S**
(45) **Date of Patent:** **** Jan. 25, 2011**

(54) **TRAY ASSEMBLY FOR A DISPENSING CONTAINER**

(75) Inventors: **John A. Gelardi**, Wake Forest, NC (US);
Ryan A. Bailey, Raleigh, NC (US)

(73) Assignee: **RJ Reynolds Tobacco Company**,
Winston-Salem, NC (US)

(**) Term: **14 Years**

(21) Appl. No.: **29/356,296**

(22) Filed: **Feb. 23, 2010**

(51) **LOC (9) Cl.** **09-07**

(52) **U.S. Cl.** **D9/456; D9/455**

(58) **Field of Classification Search** **D9/761, D9/759, 756, 708, 709, 702, 456, 455, 454, D9/453, 445, 443, 436, 435, 434, 439; 53/412; 248/146; 229/120; 222/109; 220/4.23; 219/439; 215/305; 206/529, 427; D3/304, D3/295**

(57) **CLAIM**

The ornamental design for a tray assembly for a dispensing container, as shown and described.

DESCRIPTION

FIG. 1 is a top front perspective view of a tray assembly for a dispensing container in accordance with the present design, the tray assembly having an opaque cover portion;

FIG. 2 is a top side perspective view thereof;

FIG. 3 is a top plan view thereof;

FIG. 4 is an exploded front view thereof; and,

FIG. 5 is an exploded side view thereof.

The broken lines shown herein depict environmental subject matter only and form no part of the claimed design.
